UNITED STATES PATENT OFFICE.

WALTER E. INGHAM, OF NEWINGTON, CONNECTICUT, ASSIGNOR TO PRATT & WHITNEY COMPANY, OF NEW YORK, N. Y., A CORPORATION OF NEW JERSEY.

HEADSTOCK BRAKE.

Application filed June 10, 1921. Serial No. 476,522.

To all whom it may concern:

Be it known that I, WALTER E. INGHAM, a citizen of the United States, residing at Newington, in the county of Hartford and 5 State of Connecticut, have invented certain new and useful Improvements in Headstock Brakes, of which the following is a specification.

This invention relates to brake mechanisms and particularly to such mechanism as applied to the headstock of a lathe or like machine.

It is the principal object of the invention to provide an improved brake for this purpose which will be simple in form, convenient to operate and occupy a minimum of space on the machine.

It is an object of the invention to provide a brake, the brake shoe portion of which is 20 located within the frame of the machine and the operating portion placed in a position most convenient to the operator.

With these and other objects in view, my invention consists in the features of construction and operation set forth in the following specification and illustrated in the accompanying drawing. In such drawing annexed hereto and forming a part of this specification, I have shown my invention as 25 embodied in a lathe headstock but it will be understood that the invention can be otherwise embodied and that the drawing is not to be construed as defining or limiting the scope of the invention, the claims appended 30 to this specification being relied upon for that purpose.

Referring to the figures of the drawings:

Figure 1 is a fragmentary plan view of a lathe headstock showing the invention embodied therein.

Fig. 2 is a fragmentary side elevation of the same, a portion thereof being shown in section.

A lathe operator, when desiring to stop 45 the rotation of the headstock spindle, quite commonly places his hand flat on the cone pulley thereof. The present invention provides a mechanical brake so formed and located on the headstock that the operator 50 may, by this same habitual movement of his hand, apply the brake to stop the rotation of the spindle. The invention furthermore provides that the greater portion of the 55 brake shall be located within the headstock frame or casing, the exterior portion thereof

being in the form of a hand plate lying close to the headstock frame and adapted to receive the hand of the operator to apply the brake in the same manner that he would ordinarily place his hand on the pulley. 60 The brake is preferably pivoted to the headstock frame and may be constructed as illustrated in the drawing and hereinafter described.

In the drawing, I have illustrated a headstock comprising a frame or casing 1 within which is rotatably mounted a spindle 2 provided with a face plate 3 and a center 4. The means for driving the spindle is illustrated as comprising a cone pulley 5. 65 70

The brake comprising the invention is in the form of a lever 6 pivoted intermediate its ends at 7 on the frame or casing 1. One end of the lever extends downwardly at 8 through an opening 9 in the casing and laterally at 10. The portion 10 extends beneath the pulley 5 and is provided with a brake shoe 11 for engaging the pulley. The other end of the lever is preferably in 75 the form of a plate 12 and extends over the casing as illustrated. This plate 12 may be mounted in a substantially horizontal position and is preferably curved to the contour of the casing. The normal position of the 80 brake is illustrated in Fig. 2 being held in 85 such position by means of a screw 13 and a spring 14.

It will be noted that the brake, except for the operating plate 12 thereof, lies entirely within the headstock and therefore provides 90 a brake without the usual unsightly and objectionable projecting portions incident to such mechanisms. While the brake is illustrated as being located at the top of the headstock, it should be understood that the 95 location of the same in any desired position on the casing 1 is within the scope of the invention.

What I claim is:

1. A headstock brake comprising the combination of a headstock, a spindle rotatable therein, a member mounted on the spindle, an element pivoted on the headstock at a point adjacent the junction of two relatively angular portions of the element, the outer of such two portions extending over the headstock adjacent the outer surface thereof and the inner portion extending through an opening into the headstock, and a brake shoe on the inner portion adapted 100 105 110

to frictionally engage the said member when pressure radially inward of the spindle is applied to the said outer portion.

2. A headstock brake comprising the combination of a headstock, a spindle rotatable therein, a member mounted on the spindle, an element pivoted on the headstock at a point adjacent the junction of two relatively angular portions of the element, the outer 10 of such two portions extending over the headstock adjacent the outer surface thereof and the inner portion extending through an opening into the headstock, a brake shoe 15 on the inner portion adapted to frictionally engage the said member when pressure radially inward of the spindle is applied to the said outer portion, and a spring normally operative to hold the element in the disengaged position.

3. A headstock brake comprising the combination of a headstock, a spindle rotatable therein, a member mounted on the spindle, an element pivoted on the headstock at a point adjacent the junction of two relatively angular portions of the element, the outer 25 of such two portions extending over the headstock and being a plate shaped substantially to the configuration of the adjacent external surface of the headstock, the inner portion extending from the pivot through an opening into the headstock, and a brake shoe on the inner portion adapted to frictionally engage the said member when pressure radially inward of the spindle is applied to the said outer portion.

4. A headstock brake comprising the combination of a headstock, a horizontal spindle rotatable therein, a member mounted on the spindle, an element pivoted on the headstock transversely of the spindle at a point adjacent the junction of two relatively angular portions of the element, the said pivot

being horizontal and at the top of the headstock, the outer of such two portions being plate-like in form and extending horizontally over the headstock and the inner portion extending through an opening into the headstock, and a brake shoe on the inner portion adapted to frictionally engage the said member when pressure radially inward of the spindle is applied to the said outer portion. 45

5. A headstock brake comprising the combination of a headstock, a spindle rotatable therein, a member mounted on the spindle 50 and having an inner surface concentric therewith, a double L-shaped element comprising three relatively angular portions, the element being pivoted on the headstock at a point adjacent the junction of two of 55 the said portions, the outer of such two portions extending over the headstock and the intermediate portion extending through an opening into the headstock, and a brake shoe on the third portion adapted to frictionally engage the said inner surface when pressure radially inward of the spindle is applied to the said outer portion. 60

6. A headstock brake comprising the combination of a headstock, a horizontal spindle 65 rotatable therein, a pulley on the spindle for driving the same, the pulley having an inner surface concentric with the spindle, an element mounted on a horizontal pivot at the top of the headstock and extending 70 horizontally thereover, a brake shoe adjacent the said inner surface of the pulley, and an operative connection from the element to the brake shoe whereby downward pressure on the element will frictionally engage the shoe with the said surface. 75

In testimony whereof, I hereto affix my signature.

WALTER E. INGHAM.
